UNITED STATES PATENT OFFICE.

HABIB SHAMIAH, OF BROOKLYN, NEW YORK, AND GEORGE WITTY, OF JERSEY CITY, NEW JERSEY.

PLASTER-BOARD.

No. 914,317.

Specification of Letters Patent.

Patented March 2, 1909.

Application filed May 20, 1908. Serial No. 433,895.

To all whom it may concern:

Be it known that we, HABIB SHAMIAH, a citizen of the United States, residing at Brooklyn, in the county of Kings and State 5 of New York, and GEORGE WITTY, a citizen of the United States, residing at Jersey City, in the county of Hudson and State of New Jersey, have invented new and useful Improvements in Plaster-Boards, of which the 10 following is a specification.

This invention relates to plaster boards, the object of the invention being to provide a plaster board composed of absolutely fire-proof material, and which will not crack, peel 15 or become detached, which is "browned", or cured ready for use, and which is superior in other respects to the plaster boards in common use.

A further object of the invention is to provide 20 a plaster board having reduced ends for connection with the meeting ends of adjacent boards at the joints, and a novel construction of means for use in conjunction with such reduced ends to fasten the same to the 25 framing, which fastening means when applied will not project beyond the surfaces of the boards.

In the accompanying drawing illustrating 30 the invention, Figure 1 is an elevational view of a portion of a partition frame showing the application of several boards embodying the invention thereto. Fig. 2 is a sectional plan view of the same. Fig. 3 is a perspective view of one of the joint plates.

The boards 1 may be of conventional rectangular or oblong rectangular form or of any other suitable form, as occasion may require. They are made in practice of a composition 35 consisting, preferably, of fine ashes, two parts; sharp sand, one part; Portland cement, one part; rock lime, one part; and plaster of paris, one part, mixed with water to form a plastic mass and shaped into form in a suitable mold. A plaster board formed of 40 this particular composition when dry is "browned" or cured ready for immediate use without subsequent treatment, and is of such a texture as to permit it to be sawed or cut in a cleanly manner or without chipping 45 it, and when applied will not crack, peel or break under all ordinary conditions of service. Nails may be driven through the board 50

without injury thereto, an advantage of consequence over ordinary plaster boards, which are frequently broken or otherwise injured 55 during the process of nailing them to the framing. These advantages are secured by the use of ashes in connection with sand and cement, whereby a somewhat porous composition is produced in which the elements 60 cohere sufficiently to permit penetration by nails without fracture and to enable the material to cling close to the nails, as well as to adapt the material to take up particles of wall plaster to insure a firm bond between 65 the plaster and boards in smooth-finishing the wall and closing the joints between the boards and binding the same together. The ingredients named further insure the production of a plastic composition which will not 70 set too hard or too quickly and hence may be more easily shaped in a mold, and the production of a board therefrom to which paste will more firmly adhere in applying the wall paper directly to the wall formed by the 75 boards.

Each board is halved at its ends or formed in its face portion at each end with a transverse recess 2, leaving a reduced portion 3. In the application of the boards to the beams 80 or frame pieces 4 of a ceiling, partition or side wall, the boards may be intermediately secured to certain of the partition pieces by suitable fastening nails 5, the horizontal rows or tiers of boards being arranged to break 85 joint in the customary manner. The reduced ends of the boards of each tier may abut or come in close relation, but are preferably spaced a slight distance apart for the passage of fastening nails 6 entering the adjacent beam or frame piece. These nails extend through apertures 7 in a series of joint plates 8, which extend across or bridge the reduced portions 3 and seat within the recesses 2, so that they clamp the reduced ends 90 of the boards against the frame piece. By this means the meeting ends of the boards at the joints are securely fastened in position, and the surfaces of the plates lie flush with the faces of the boards, so that the ordinary 100 wall paper may be applied without injury or showing irregularities of surface.

The construction described adapts the boards to be quickly and conveniently ap-

plied without the use of laths and without soiling the floor of the room, and, as the material of which they are composed does not disintegrate and is not easily broken or injured, durability is insured and the cost of repairs reduced to a minimum.

Having thus fully described the invention, what is claimed as new is:—

A plaster board formed from a combination of ashes, two parts; sand, one part; Port-

land cement, one part; lime, one part; plaster of paris, one part; and water.

In testimony whereof we affix our signatures in presence of two witnesses.

HABIB SHAMIAH.
GEORGE WITTY.
